US0D1047774S

(12) **United States Design Patent** (10) Patent No.: **US D1,047,774 S**
(45) Date of Patent: ** Oct. 22, 2024

(54) **MOTORCYCLE**

(71) Applicant: **TAIZHOU HUANGYAN JUFENG MOTORCYCLES CO., LTD.**
Zhejiang (CN)

(72) Inventor: **Hui Chen**, Taizhou (CN)

(**) Term: **15 Years**

(21) Appl. No.: **35/521,024**

(22) Filed: **May 6, 2024**

(80) **Hague Agreement Data**

Int. Filing Date: **May 6, 2024**

Int. Reg. No.: **DM/237193**

Int. Reg. Date: **May 6, 2024**

Int. Reg. Pub. Date: **May 31, 2024**
